UNITED STATES PATENT OFFICE

MATHEW M. EGAN, OF FORT WORTH, TEXAS

PROPELLER

Application filed February 17, 1930. Serial No. 429,171.

As is well known by aeronautical engineers and experts a rapidly rotated propeller frequently churns the air and such air getting away from the propeller materially and at 5 times seriously decreases the efficiency of the thrust of the propeller and creates what is termed a "slip".

It is the object of this invention to effectively overcome such contingency by the provision of means for banking or wedging the air against the propeller to provide a tangible substance that will offer the proper and desired resistance to the thrust of the propeller.

In carrying out my invention I aim to provide 15 an auxiliary propeller which is arranged at the front of the main propeller, which auxiliary propeller has its blades arranged at a different pitch from the blades of the main propeller and which auxiliary propeller is arranged at a less ratio of speed than the main propeller and wherein the auxiliary propeller will supply air to the main propeller, causing the air to become alive or become tangible to the opposite thrust of the blades of the main 20 propeller, the blades of both the auxiliary and main propellers feeding air in the same direction but at opposite angles so that such air meeting the blades of the main propeller is grasped, delivered and directed by such 25 blades at an angle different to the course of the air started by the auxiliary propeller and thereby eliminating the slip.

It is also my purpose to provide means for the overcoming of cavitation by having the 30 front or auxiliary propeller running in an anti-clockwise direction (facing propeller assembly) at a normal or less speed than that of the main propeller so that the auxiliary propeller will force back a current of air to meet the blades of the main propeller, which main propeller is revolved in a clockwise direction and thereby causing the blades of the main propeller, which is rotated at a greater speed than the auxiliary propeller, to take 35 care of the air supplied by the auxiliary propeller and thus overcoming any vacancy or vacuum which is naturally caused by high speed single propeller blades or in other words to bank or wedge the live air between 40 the two blades which are revolved in oppo-

site directions so that such air becomes a tangible substance which is placed in a position to be handled or to be acted upon at a greater advantage by the main propeller.

A further object resides in the provision 55 of means for mounting both of the blades upon the engine shaft and for increasing the speed of the main propeller with respect to the speed of the auxiliary propeller.

To the attainment of the foregoing and 60 other objects which will present themselves, the improvement further resides in certain other novel features of construction, combination and operative association of parts, one satisfactory embodiment of which is disclosed by the accompanying drawings.

In the drawings:

Figure 1 is a side elevation of propellers in accordance with this invention, parts being broken away and parts in section.

Figure 2 is a sectional view approximately on the line 2-2 of Figure 1.

Figure 3 is a front elevation of the improvement.

Figure 4 is a diagrammatic view to more 75 clearly illustrate the manner in which the air is wedged between the auxiliary and main blades.

Referring now to the drawings in detail, the numeral 1 designates a portion of the engine frame, and 2 the engine drive shaft. On 80 the outer and reduced end of the shaft 2 there is fixedly secured the auxiliary air directing propeller 3. From the hub of the propeller extend oppositely directed blades 85 4, and the said blades are arranged at desired angles.

On the outer face of the engine frame 1 there are fixed the short or stub shafts 4' on which are journaled pinions 5. These pinions are in mesh with the gear wheel 6 which is fixedly secured on the shaft 2. The pinions carry on their outer faces other and larger pinions 7. It is to be noted that the pinions 5 and 7 are respectively three in number 90 and are equidistantly spaced and the pinions 7 are in mesh with an internal ring gear 8 on the flange of a case or housing 9 that encloses the pinions and gears that constitute 95 the planetary speed increasing gearing.

100

Fixed on the outer face of the housing 9 there is the hub portion 10 of the inner and main or power propeller and the angular pitch of the oppositely directed blades 11 of the power or main propeller is opposite to the pitch of the blades 4 of the auxiliary propeller 3.

The hub of the main or power propeller does not have a direct bearing on the shaft 2, the said hub having let through the center thereof and secured thereto a bearing sleeve 12 that has on its ends flanges 13 and the outer flange is provided with an annular groove that affords one of the elements of a race-way for anti-frictional bearings 14. The second element of the race-way is provided with a flanged end of a thrust bearing sleeve 15 which is arranged around the shaft 2 and which is in contact with the inner face 20 of the hub of the auxiliary propeller 3.

The auxiliary propeller 3 turns at a materially less speed than that of the main propeller, and likewise is rotated in an anti-clockwise direction, facing the propeller assembly, while the main propeller travels in a clockwise direction. The comparatively slowly rotating auxiliary propeller, having its blade arranged at an opposite angle to the blades of the main propeller will take up and feed air to the main propeller, bunching or wedging such air so that the blades of the main propeller traveling at a comparatively great speed will take hold of the air thus supplied and such air becoming a tangible substance offers a resistance to the thrust of the main propeller so that the danger of "slips", is entirely overcome. As a matter-of-fact, the auxiliary propeller forces the current of air against the main propeller and the main propeller will likewise force the air against the auxiliary propeller and because of the difference in the ratio of speed between the main and auxiliary propeller no vacancy or vacuum which is naturally caused by a high speed single propeller blade can occur.

The above principle is also applicable to water propulsion either as a tractor or a propeller, the speed being altered as is also the pitch of the blade to suit the particular case.

Figure 3 illustrates the manner in which the blades are reversely turned and Figure 4 illustrates by diagram the manner in which the air is wedged between the auxiliary and the main propellers. The diagram in Figure 4 discloses clearly the method employed in compressing the air stream to give a tangible substance with more density and thereby increasing the power produced by the sum total 60 of each propeller running singly, such power being increased from three to five times more than that of the ordinary propeller now in use.

The two propeller blades are to be shaped and set at a proper angle to handle air stream

at the best advantage. The auxiliary propeller always brings the proper air stream to supply the main blade regardless of the wind direction. The gear used in reversing the main blade or blades is an increased internal gear ratio, and, as above stated, causes the main blade to revolve faster or slower as the case may be, in proper relation to the auxiliary blade that feeds air to the main blade.

From experience I have found that propellers constructed in accordance with my invention will work equally well on lower speeds such as the Diesel engine and can be used on a separate shaft with proper bearings, powered by two different engines or motors in an air shaft or tunnel through a plane or dirigible and that the speed can be reduced fifty percent with very little loss in efficiency of my improved air wedging propeller. The propellers navigate air at a much less density than the ordinary well known propeller, thereby increasing the ceiling.

The propeller having a reversed motion acts as a stabilizer by the gyroscopic effect giving the plane no drift or pull as by propellers which revolve in only one direction. The speed of the landing plane is much lower than can be attained by single propellers, because the engine handling two blades is more flexible and the propellers revolving in opposite directions give less vibration to the craft and as stated is easier on the engine on account of gyroscopic effect.

It is to be noted that in all cases the front or auxiliary propeller is to be revolved in a direct manner with the engine speed, and the main blade is revolved at a faster speed, this being the most efficient ratio on account of the reduction of the revolutions permitted of the engines. It is, of course, possible to obtain the same power ratio or step up of power by revolving the auxiliary blade even faster than the main blade as the air is acted on by the same wedging principle and also if desired more blades may be added to the construction.

Having described the invention, I claim:

A propulsion for flying machines comprising an auxiliary propeller secured to a power shaft, an anti-friction bearing on the shaft and spaced from the hub of the propeller, a main propeller having the hub thereof mounted on the bearing for free rotation relative to the shaft, a spacing sleeve on the shaft and engaging at one end the hub of the auxiliary propeller and having anti-friction engagement with the bearing at the other end, and a planetary transmission between the shaft and the hub of the main propeller for rotating the latter at a different speed of rotation from the speed of rotation of the auxiliary propeller and in a reverse direction thereto.

In testimony whereof I affix my signature.

MATHEW M. EGAN. 130
